[57] CLAIM

The ornamental design for a two sided abrading mit with dual soap compartments for face and body use, as shown and described.

DESCRIPTION

FIG. 1 is a perspective view of two sided abrading mit with dual soap compartments for face and body use, showing my new design;

FIG. 2 is a right side elevational view thereof;

FIG. 3 is a top plan view thereof;

FIG. 4 is a bottom plan view thereof;

FIG. 5 is a front elevational view thereof; and

FIG. 6 is a rear elevational view thereof;

The left side elevational view is a mirror image of the right side elevational view.
